UNITED STATES PATENT OFFICE

RICHARD SANDER, OF CURITYBA, BRAZIL

SOUND BOARD FOR PIANOFORTES AND THE LIKE

Application filed February 5, 1930, Serial No. 426,126, and in Germany February 2, 1929.

My invention relates to improvements in soundboards for pianofortes and the like, and one of the objects of the improvements is to provide a soundboard in which the bridge or bridges on which the strings are supported are constructed so that the sound is intensified and improved. In instruments having crossing strings two bridges are provided, a long bridge curved in the manner of a harp 10 for supporting the descant strings, and a short one for supporting the crossing bass strings, and on the said bridges two pins are provided for each string, the said strings being deflected out of line by one of the pins and turn back into a direction parallel to the line of its main portion by the second pin.

In my improved soundboard the said bridges are divided along their median line thus producing two bridge bars running parallel to each other a small distance apart in lieu of a single one, and each bridge bar is provided with a series of pins so that each string bears on pins fixed to both bridge bars. While in constructions now in use in which both series of pins are fixed to an integral bridge the pressures exerted thereon from opposite sides are balanced within the bridge, in my improved construction the said pressures and the vibrations of the strings are transmitted to the soundboard. Another object of the improvements is to construct the bridge for supporting the bass strings so that the vibrations of the said bass strings are transmitted to a part of the soundboard capable of unimpeded vibration, and with this object in view my invention consists in supporting the bass bridge on a rockable lever bearing on a suitable portion 30 of the soundboard and preferably below the bridge supporting the descant strings. Thereby the pressures exerted by the descant and bass strings on the soundboard are compensated, so that the soundboard is relieved 40 of the strain and is capable of following freely the acoustic vibrations of the strings.

For the purpose of explaining the invention an example embodying the same has been shown in the accompanying drawing in which the same reference characters have been

used in all the views to indicate corresponding parts. In said drawing,

Fig. 1 is a top plan view showing a part of a soundboard, and the bridges and the strings mounted thereon,

Fig. 1a is a detail, partly in section, showing spacing means for the bridge bars,

Fig. 2 is a sectional elevation on an enlarged scale taken on the line 2—2 of Fig. 3,

Fig. 3 is a bottom view of the soundboard, and

Fig. 4 is a detail sectional view on an enlarged scale showing a part of the bridge supporting the descant strings.

In the example shown in the drawings two 65 bridges are mounted on the soundboard *e* and each bridge is divided longitudinally into two bridge bars *d*¹, *d*² and *b*¹, *b*² respectively, the said bridge bars being located parallel to each other and a small distance apart. The bridge 70 bars *d*¹, *d*² are provided for supporting the descant strings, and the bridge bars *b*¹, *b*² supports the bass strings. The first series of pins *t* as viewed from the side of the wrest 75 plank is secured to the bridge bars *b*¹ and *d*¹ and the second series of pins *t* is secured to the other bridge bars *b*² and *d*². The bridge bars can be reinforced relatively to each other by inserting suitable spacing members such as screws *r* between the same, the 80 said spacing members preferably ending at points above the soundboard.

The pressures exerted by the strings on the pins *t* in opposite directions are transmitted through the bridge bars *d*¹, *d*² and *b*¹, *b*² to the soundboard, so that also the acoustic vibrations of the strings are also transmitted to the said soundboard.

The bridge *b*¹, *b*² supporting the bass strings is not supported directly on the soundboard, but on a plate *p* connected by means of pillars *u* with the ends of levers *c* rockingly supported below the soundboard on brackets *n*, the pillars *u* being passed through holes made in the soundboard *e*. At their 90 opposite ends the levers *c* bear on the bottom side of the soundboard at parts below the descant bridge *d*¹, *d*², blocks *l* of hard wood or the like and set screws being preferably 95 provided for permitting regulation of the 100

pressure of the levers on the soundboard. Thus the pressure of the bass strings acts on the soundboard in a direction opposite to the direction of the pressure of the descant strings, so that the said pressures are compensated, and the soundboard is relieved of the strain caused by the said pressures. Therefore the soundboard follows the acoustic vibrations of the strings more freely than in constructions in which the soundboard is put under tension by the pressure of the strings.

Preferably the strings are arranged so that the deepest bass string is connected with that part of the soundboard the natural vibrations of which have the greatest amplitude. Thereby two of the rocking levers *c* cross each other in the manner shown in Fig. 3.

20 When disposing the parts *c* on the soundboard the room needed for the levers *c* must be taken into consideration.

The highest descant strings are located on a part of the soundboard which has comparatively unfavourable vibrations. In my improved soundboard the pressure of the descant strings is transmitted to a part of the soundboard which has a better vibration. For this purpose the end of the descant bridge *d*¹, *d*² is connected by a rocking lever *c*₀ with a portion of the soundboard having a better vibration, as is shown in Fig. 3. For this purpose the bottom sides of the bridge bars *d*¹ and *d*² are recessed or flattened at their ends, as is shown in Fig. 4, so that the said end portions are out of contact with the soundboard, and the said end portions are connected with a plate *q* or the like which is connected with the rocking lever *c*₀ located below the soundboard by means of a screw *h*.

40 The intensity of the sound can be varied according to the position of the fulcrums *a* relatively to the length of the rocking levers *c*.

I claim:

45 1. In a pianoforte or the like, a soundboard, a bridge fixed thereto and comprising substantially parallel bars connected directly to the soundboard and spaced from one another, pins secured to said bars, and strings each 50 engaging one of the pins of each bar.

2. In a pianoforte or the like, a soundboard, a bridge fixed thereto and comprising substantially parallel bars connected directly to the soundboard and spaced from one another, means for spacing said bars from each 55 other, pins secured to said bars, and strings each engaging one of the pins of each bar.

3. In a pianoforte, a soundboard, a bridge, strings attached to said bridge, and rocking 60 levers supporting said bridge and bearing on a portion of the soundboard remote from said bridge.

4. In a pianoforte, a soundboard, bridges, one engaged by the descant strings and the 65 other engaged by the bass strings, a plate on

which the bridge supporting the bass strings is mounted, and rocking levers at the side of the soundboard opposite to the bridge, said rocking levers supporting said plate and bearing on the soundboard at a part remote from 70 said plate.

5. In a pianoforte, a soundboard, bridges, one engaged by the descant strings and the other engaged by the bass strings, a plate on which the bridge supporting the bass strings 75 is mounted, and rocking levers at the side of the soundboard opposite to said bridge, said rocking levers supporting said plate and bearing on the soundboard at parts opposite to the bridge supporting said descant strings. 80

6. In a pianoforte, a soundboard, a bridge supporting the bass strings, and a rocking lever supporting said bridge at the part engaged by the deepest string and bearing on a part of the soundboard remote from said 85 string and capable of vibration of high amplitude.

7. In a pianoforte, a soundboard, a bridge mounted thereon, strings attached to said bridge, and a rocking lever at the side of the 90 soundboard opposite to said bridge, said lever supporting said bridge at the part engaging the highest string and bearing on the soundboard at a part remote from said bridge and capable of higher vibration. 95

In testimony whereof I affix my signature.

RICHARD SANDER.
